UNITED STATES PATENT OFFICE.

DANIEL A. WEDMORE, OF PHILADELPHIA, PENNSYLVANIA.

BOTTLE-BASKET.

1,070,212.

Specification of Letters Patent. Patented Aug. 12, 1913.

Application filed August 27, 1910. Serial No. 579,251.

To all whom it may concern:

Be it known that I, DANIEL A. WEDMORE, a citizen of the United States, residing in Philadelphia, Pennsylvania, have invented 5 certain Improvements in Bottle-Baskets, of which the following is a specification.

My invention relates to carriers for bottles and similar objects, and the object of my invention is to provide a metal basket 10 of simple construction and one that is specially reinforced and therefore substantially indestructible.

My invention is shown in the accompanying drawings, in which:

15 Figure 1, is a perspective view of my improved basket; Fig. 2, is a longitudinal section of the same, and Fig. 3, is a cross sectional view.

The basket proper is made of flat metal 20 strips indicated at 1, 2 and 3, suitably secured together at the crossing points; for instance by means of rivets 4. The strips 1 run lengthwise of the basket at the bottom and have upturned ends 5; the strips 2 run 25 crosswise and have upturned ends 6, and the strips 3, which are substantially continuous encircle the structure and are connected to the upturned ends 5 and 6. Crossing strips 7 and 8, the former extending lengthwise and the latter crosswise of the structure, form compartments for the reception 30 of bottles or other articles.

To form supporting means for the structure, a handle is provided, made up of a 35 plurality of independent metal strips, some of which are connected to the bottom strips 1 and others to the longitudinal and cross partition strips 7 and 8. This handle comprises strips 9 connected at the junction of one of the 40 bottom cross strips 2 with one of the longitudinal strips 1 and also to the crossing strips 8 forming the partitions, and such strips 9 have a substantially straight portion at the top. 45 Of this form of handle strip two are provided. In addition, there are two other strips 11 connected to the longitudinal partition strip 7, one of said strips 11 having outwardly extending legs, and the other having inwardly extending legs. The strips 11 50 forming these legs have straight portions at the top adjacent the straight portions 10 of the other legs, and the several plies of straight portions are inclosed by a tubular

member 12. This may be of any suitable form or material, but in the present instance 55 it is shown as formed of a wire coil, which may have its convolutions soldered together so as to provide a smooth grip.

The basket or carrier constructed in accordance with my invention is particularly 60 strong and will stand an enormous amount of hard usage; a condition to which such baskets are usually subjected.

In addition to riveting the strips together, the several joints may be soldered, and when 65 completed the whole basket is given a coating of tin or other suitable agent that will prevent rust or oxidation.

I claim:

1. A basket made of a plurality of metal 70 strips adapted to form a supporting structure, and a plurality of strips extending horizontally between the walls of such basket and forming bracing means for such structure, in combination with a handle comprising a plurality of flat strips or bars, 75 some of which bars are secured to the bottom of the basket, while the others are secured to said bracing members, all of said handle bars extending diagonally from a 80 common meeting point to the basket and its bracing means, and the bars which are secured to the bracing means extending fore-and-aft of those handle bars which are secured to the bottom of the basket. 85

2. A basket made of a plurality of metal strips crossing each other and adapted to form a supporting structure, and bracing means for such structure, in combination with a handle comprising a plurality of flat strips or bars, some of which bars are secured to the bottom of the basket, while the others are secured to said bracing means, all of said handle forming strips extending diagonally to a common meeting point, and 90 the bars which are secured to the bracing means extending fore-and-aft of those handle bars which are secured to the bottom of the basket. 95

In testimony whereof, I have signed my 100 name to this specification, in the presence of two subscribing witnesses.

DANIEL A. WEDMORE.
